UNITED STATES PATENT OFFICE.

JOHN EDWARD THORNTON, OF LONDON, ENGLAND.

CINEMATOGRAPH-FILM MATERIAL.

Original application filed May 5, 1924, Serial No. 711,255, and in Great Britain May 18, 1923. Divided
and this application filed October 3, 1925. Serial No. 60,348.

This invention relates to film material for the production of transparent multi-color cinematograph film-positives in four or three colors.

5 In my application Serial No. 711,255, filed May 5, 1924, of which this application is a division, I have described a cinematograph film-positive built up of two thin strips of film material produced by printing two picture components in different colors one upon each side of both film strips and cementing the two printed colored strips together into a complete multi-color film positive.

10 This invention consists of a film-material therefor comprising a strip of celluloid or other water-proof material of double standard width and half standard thickness and a layer of colored colloid in two stripes on each side of the celluloid film.

15 20 The invention will be described with reference to the accompanying drawing in which: Fig. 1 is a perspective view of a film embodying the invention.

25 Fig. 2 is a cross-section of a four color film embodying the invention as viewed at a right angle to its length, wherein a light-obstructing dye is incorporated with the substrata.

30 Fig. 3 is a view, similar to Fig. 2, of a three color film embodying the invention.

35 Fig. 4 is a view, similar to Fig. 2, wherein a light-obstructing dye is incorporated with the colored layers, and

40 Fig. 5 is a view, similar to Fig. 2, wherein soluble and light-obstructing layers from which the colors may be removed are interposed between the transparent support and the layers of colored emulsion or colloid.

45 The film-material is manufactured with a transparent central base A of celluloid (or similar water-proof material) of only about .00100 inch thick, and of double standard width so that all the four section-images can be printed, developed, and dried simultaneously to secure uniform density and color balance in all images and also to ensure uniform expansion and contraction. When the double-width print is finished and dried it is slit into two separate strips. The colored colloid consists of gelatine, albumen, fish-glue or the like with which suitable dyes or other coloring matter is incorporated.

50 To both sides of the base A of thin double width material an adhesive substratum B of

the usual type is applied, of about .00005 inch in thickness (though it may be thinner) and 55 upon this each side is coated with a layer of colored colloid, arranged as two parallel stripes C', C² of different colors upon each side (four stripes in all) which run longitudinally of the film. These layers are preferably made 60 about .00090 inch thick each, but may be slightly more or less. The adhesive substratum serves to indissolubly unite the colored colloid stripes to the central transparent waterproof base. 65

The colored layers require to be sensitive to light, and may be sensitized by various processes.

In one method the colored film may be stored and is rendered sensitive before use by 70 treatment in a bath of a suitable bichromate salt and then drying. When such film is exposed under a negative or positive the colloid is rendered insoluble in parts and at those points the coloring matter is permanently locked up with the insoluble colloid thus forming the image, whilst at other points it remains free and can be washed out or removed.

In another method, suitable salts of iron 80 may be substituted for the bichromate salts, as used in several well-known printing processes.

In another method the colored colloid is sensitized with salts of silver. These may be 85 applied as a bath in the same way as the salts of bichromate or iron, as used in well-known print-out processes.

In another method the colored colloid and silver salts are formed into an emulsion, as in 90 the well-known gelatino-silver-bromide or gelatino-silver-chloride printing processes.

In whichever of these methods is adopted for rendering the colored colloid sensitive to light, the necessary coloring matter is incorporated with the colloid at the time of manufacturing the film, and the coloring matter not required in the image is washed out or removed from the colloid by suitable re-agents after printing and developing. 100

The coloring matter used in forming the image itself can be rendered still more permanently fixed by the application of suitable mordants, all in manner well-known.

The methods of printing a film sensitized 105 according to any of the different sensitizing

processes, and the different treatment required in the development, and other processes after printing, are all well-known to those acquainted with each process; they form 5 no part of the present invention and are therefore not described in detail herein.

For a four-color film, as shown in Figs. 1, 2, 4 and 5, the colors preferred are crimson-red, blue-green, yellow, and blue-violet, but 10 these colors may be slightly modified if desired.

The colored colloid is applied to the double-width strip of transparent waterproof base or support in the form of two parallel 15 stripes C' , C^2 of two different colors upon one side of the support and two parallel stripes C' , C^2 of two other colors upon the other side of the support.

It is preferred to place the red and green 20 back-to-back and the yellow and violet back-to-back. But if desired this order of arrangement may be varied.

For a three-color film, as shown in Fig. 3, the colors preferred are red, blue and yellow; 25 but it is obvious that they may be other colors.

As in this arrangement there are only three colors to fill four places upon the double-width support, one of the three colors is duplicated upon each half-width of the strip.

30 Therefore, in the form using red, blue and yellow, it is preferred to place the red and yellow back-to-back, and the blue and yellow back-to-back. But if desired this order of arrangement may be varied.

35 As such a sensitized strip is intended to be printed upon both sides simultaneously by being sandwiched between two negatives and exposed to light from opposite sides, it is necessary to adopt means for preventing 40 penetration of light through the film and thus wrongly affecting the sensitive layer upon the opposite side.

This is preferably effected in known manner by providing the central base with a soluble light obstructing color or dye E which can 45 be removed by washing out after printing, during the after operations of developing, fixing or washing. For this purpose a number of dyes are suitable, such for example as 50 tartrazine and others. The dye may be incorporated with the thin substratum layers at the time of their application to the central support. Or in some cases a soluble yellow 55 dye may be incorporated with the colored layers, but this depends upon the nature of the sensitizing and of the coloring matter used to form the images. In practice the first method is preferred as the simplest.

Films constructed with the light-obstructing 60 layers E as described are intended to be printed only from negatives of the "full-tone" description, the sensitized film being sandwiched between the two negatives during the operation of printing, and the exposures 65 can be made either by contact or by

projection, according to speed of the sensitized material.

With "full-tone" negatives the light-obstructing layers E are essential.

With a double-width sensitized film constructed as described, and a pair of suitable double-width negatives, all four images can be printed simultaneously and automatically at one printing operation without the necessity of a large amount of highly skilled labour, and the various subsequent operations of developing, fixing, washing, mordanting, color-removing, or the like can also be effected by automatic machinery that will ensure equal treatment of all four sections of the 75 same picture.

Moreover the invention obviates the uncertainty of result and great expense in adjusting the colors which would be necessary if non-colored sensitized film were used and the four images colored after development by the known processes of dyeing for each color separately. A more certain quality of result is obtained owing to the coloring matter for each section being incorporated with the sensitized layer at the time of its manufacture in exact and carefully adjusted amounts that will give correct color-balance in the finished multi-color picture. The invention although primarily intended for the 90 production of cinematograph positive pictures will be found equally applicable to other multi-color photography (non-cinematograph).

Although the complete film is herein described as a double-width strip, it may for convenience and economy in manufacture be formed as a wide web of several strips, as usual in manufacturing most sensitized material, the web being slit into a number of 100 double-width strips afterwards.

Although the coloring matter can be incorporated with the colloid mixture before the film support is coated as strips, I prefer 110 the following method of manufacture.

The wide web, or alternatively the double-width strip A, is first covered all over upon both sides by a suitable coating machine with non-color colloid D, either of the ready-sensitized or non-sensitized variety. After drying 115 it is next passed through a machine which applies the solutions of coloring matter or dyes in the form of colored stripes C' , C^2 each being the width of a single film. These solutions are each adjusted to the correct 120 strength or intensity of color and are applied until the colloid is charged to saturation and the colors have penetrated the entire thickness of colloid down to the waterproof base or support.

If necessary the colors may be mixed with a mordant; or the mordant may be incorporated with the colloid before the colors are applied; or the mordant may be applied last of all, after coloring.

The web or strip is dried and is then ready for use.

What I claim as my invention and desire to protect by Letters Patent is:—

- 5 1. A cinematograph positive film material comprising a strip of waterproof material of double standard width and half standard thickness, a layer of colored colloid in two parallel differently colored stripes on one side of said strip and a layer of differently colored colloid in two parallel stripes on the other side of said strip and running in the same direction as said first named stripes, said strip adapted to receive four component 10 image impressions and to be severed into two and to have its two portions cemented together to assemble and superimpose the four component images in one picture space.
- 15 2. A cinematograph positive film material comprising a strip of waterproof material of double standard width and half standard thickness, a layer of colored sensitized colloid in two parallel colored stripes on one side of said strip and a layer of colored sensitized colloid in two parallel stripes on the other side of said strip and running in the same direction as said first named stripes, each of the four stripes differing in color from the other three, said strip adapted to receive 20 four component image impressions and to be severed into two and to have its two portions cemented together to assemble and superimpose the four component images in one picture space.
- 25 3. A cinematograph positive film material comprising in its construction a central base-layer of transparent waterproof material about .00100 inch thick; a layer of adhesive substratum about .00005 inch thick applied to each face of said base layer; a layer of colored colloid about .00090 inch thick applied to each of the substratum layers; and a light obstructing removable dye; the substratum, colored colloid and light-obstructing dye 30 being applied in two parallel stripes to the full width and to both sides of the double width central base, making a total of four parallel stripes, each of said four stripes differing in color from the other three.
- 35 4. A positive film material comprising in its construction:—(A) a double-width strip or support of transparent waterproof material; (B) two parallel stripes of differently colored colloid indissolubly attached to one side of the support and comprising two of the color components for a four-color picture; (C) two parallel stripes of differently colored colloid indissolubly attached to the other side of the support and comprising the other two colors for a four-color picture, the stripes on one side of the support being parallel to those on the other side and running in the same direction as the latter; (D) a layer of adhesive substratum interposed between the central support and its colored colloid layers

upon each side of the support, to effect perfect union between the support A and its colored layers B and C.

5. A positive film material comprising in its construction:—(A) a double-width strip 70 or support of transparent waterproof material; (B) two parallel stripes of differently colored colloid indissolubly attached to one side of the support and comprising two of the color components for a four-color picture; (C) two parallel stripes of differently colored colloid indissolubly attached to the other side of the support and comprising the other two colors for a four-color picture, the stripes on one side of the support being parallel to 75 those on the other side; (D) a layer of adhesive substratum interposed between the central support and its colored colloid layers upon each side of the support, to effect perfect union between the support A and its 80 colored layers B and C; and (E) a soluble light obstructing dye, between the colored layers.

6. A cinematograph positive film material comprising in its construction a central base-layer of transparent waterproof material of double standard width and about .00100 inch thick; a layer of adhesive substratum about .00005 inch thick applied to each face thereof; a layer of colored colloid about .00090 inch 90 thick applied to each of the substratum layers; a light-obstructing removable dye between the colloid layers, said colloid being ready-colored during manufacture of the film material and formed as four complementary-colored stripes applied to the substratum layers, two of the colored stripes being arranged side by side in parallel lines running longitudinally of the strip on the front side of said base layer, and two similarly disposed colored stripes upon the back side of said base layer; the colored stripes being disposed in any desired order of combination. 95

7. A cinematograph positive film material comprising in its construction a ready colored film material of five layers and of double the width and about half the thickness of a standard film, two of said layers each comprising a pair of parallel colored stripes, the third layer comprising a central base of transparent waterproof material between said colored layers and indissolubly united therewith, and the remaining two layers each comprising a colloid layer containing a removable light-obstructing medium and each interposed between the colored layers and said central base. 110

8. A cinematograph positive film material comprising in its construction a sensitized ready colored film material of five layers and of double the width and about half the thickness of a standard film, two of said layers each comprising a pair of differently colored sensitized parallel stripes, the third layer comprising a central base of transparent 115

120

125

130

waterproof material between said colored layers and indissolubly united therewith, the remaining two layers each comprising a colloid layer containing a removable light-ob-
5 structing medium and each located between one of said sensitized colored layers and said central base.

9. A positive film-material for photographic purposes comprising a water-proof
10 base of double picture area laterally disposed

having a layer of colored colloid in two colors, one in each picture area on one side, and a layer of colored colloid in two colors, one in each picture area on the other side, the picture areas on one side being in exact register 15 with those on the opposite side.

In testimony whereof I have hereunto set my hand.

JOHN EDWARD THORNTON.
